CARD GAME.

1,332,249.

Specification of Letters Patent.

Patented Mar. 2, 1920.

Application filed August 21, 1919. Serial No. 318,882.

To all whom it may concern:

Be it known that I, SCOTT HORACE FEERO, a citizen of the United States, residing at Canton, in the county of Stark and State of Ohio, have invented a new and useful Card Game, of which the following is a specification.

This invention relates to improvements in card games and more particularly to an educational game comprising a deck of cards containing four complete alphabets, each card containing two letters, the same letter not appearing twice upon the same card and no two cards containing the same combination of letters. Upon each card is placed a number adjacent each letter on the card, the number corresponding to the position of the letter in the alphabet.

The game is more especially adapted for the use of children, to easily teach them spelling and to also impress upon their minds the position which each letter occupies in the alphabet, although different variations of the game may be played which will be exceedingly interesting to adults.

The deck comprises fifty-two cards, each card containing two letters of the alphabet, the entire alphabet thus appearing four times in the deck, thus making it possible to spell any word in the English language with the cards. A joker or card of instructions with the rules of the game is also included in the deck which may be dealt out in the ordinary manner with the other cards in the deck, and may be played "wild" in the same manner as the joker is often played "wild" in well known card games, that is the joker may be played by the party holding it at any desired time and may be called by the player any letter in the alphabet necessary to complete a word.

The objects of the invention are to provide a card game containing four complete alphabets arranged in proper combinations upon the cards to allow of the spelling of any conceivable word in the English language, to place a number upon each card adjacent each letter thereon corresponding with the position of that letter in the alphabet and to provide a card game which is not only highly instructive, but which will be exceedingly interesting and amusing not only to children but to adults as well.

With these objects in view the invention consists in the novel construction and arrangement of parts, hereinafter described, illustrated in the accompanying drawings,

and particularly pointed out in the appended claim, it being understood that various changes in the form, proportions, size and minor details of construction may be made within the scope of the appended claim, without departing from the spirit or sacrificing any of the advantages of the invention.

The invention thus set forth in general terms is illustrated in the accompanying drawings forming part hereof, in which—

The figure shows the complete deck of cards with which the game is played.

A practical embodiment of the invention is disclosed in the accompanying drawings, forming a part of this specification in which similar numerals of reference indicate corresponding parts throughout the view.

As stated above the deck comprises fifty-two cards, each bearing two letters of the alphabet, and a joker upon which may be printed the instructions for playing the game. Each letter of the alphabet appears upon four different cards, the same letter never being repeated upon a single card and the same combination of letters not being placed upon more than one card. Thus four complete alphabets are included in the deck.

By way of explanation, attention is directed to the drawing where the cards are arranged in four horizontal rows, each comprising thirteen cards, the rows being numbered from top to bottom for purpose of identification by the numerals 1, 2, 3 and 4. An examination of the upper row indicated by the numeral 1 will show that the letters indicated by the numeral 5 upon the upper portions of these cards comprise the letters of the first half of the alphabet, that is the letters from A to M, while the inverted letters upon the lower portions of these cards indicated by the numeral 6 comprise the letters of the second half of the alphabet, that is from N to Z, inclusive. Thus all of the letters of the alphabet are displayed in the thirteen cards indicated generally by the numeral 1.

An inspection of the cards in the remaining rows indicated by the numerals 2, 3 and 4 will disclose the fact that the thirteen cards in each of these rows contain a complete alphabet, the combinations of the letters upon each card, however, being different in each instance. For instance taking the four cards at the extreme right of the drawing upon which the letter M appears upon

the upper portion of each card, it will be seen that the letters Z, Q, U and N, respectively, are shown upon the lower portions of these four cards. Thus no two cards in the 5 deck are alike.

- For the purpose of impressing on the mind of the players the position which each letter occupies in the alphabet, a small number indicated generally by the numeral 7 is 10 placed adjacent each letter upon each of the cards, this number representing the position which the letter occupies in the alphabet as 1 for A, 2 for B, 3 for C, etc. A naught may be placed upon the joker in the same 15 position, if desired.

There are different variations in which the game may be played, one of which is given below. Any number of persons may play at one time, three cards being dealt to 20 each player and the remainder of the cards placed face down upon the table. The player to the left of the dealer places one card upon the table, face up, placing the card in the proper position to bring either 25 one of the letters upon said card uppermost. Supposing the card bearing the letters H and U is played, if the player desires to play the H he will turn the card with the H uppermost or vice versa, if he intends playing 30 the letter U. If necessary each player will call the letter he desires played as he plays his card upon the table. After each player has played a card he draws one card from the pack, thus each of the players will 35 have three cards in his hand until the entire pack has been drawn. The next player to the left then plays in the same manner endeavoring, however, to play a letter which will complete a word. Thus for instance if 40 he has in his hand the letter E he will play this card with the letter E up, spelling the word "He" and scoring a point in the game. Should the next player to the left hold a card containing the letter R he may play 45 this card spelling the word "Her," the game being thus continued around the table, each player endeavoring, if possible to complete a word with the letter that he plays. When it is impossible to spell any further words with 50 the combination of cards upon the table the cards already played are discarded and a new word started. Any player neglecting to call a word which he has completed before the next card is played will not count the 55 score he is otherwise entitled to, while any other player at the table observing the word which has been missed by the player completing the same may call the word and score the point himself. Any total may be 60 decided upon before starting the game as the winning score, the player first scoring this amount winning the game. Partners may play by adding their scores.

Another variation of the game which is 65 very instructive to those learning to spell is

to make up a list of words to be spelled before the game is commenced, the dealer announcing each word in turn and each one of the players having the letters to form each word playing the letters in turn. For instance supposing the first word upon the list would be "Brown," if the player to the left of the dealer has a card bearing the letter "B" in his hand he plays the card in his hand with the letter B uppermost while if 75 he has not any card containing the letter B, the play passes to the next player to his left. The next player to the left who has the letter R will play it, the playing being continued until the letter N is played, the player 80 having the letter N counting the score for word. The next word upon the list is then announced and spelled in the same manner until all of the words upon the list have been spelled or all of the cards in the deck have 85 been used up.

As there are four complete alphabets contained in the deck it is possible to spell any word in the English language as it is not known there are any words containing the 90 same letter more than four times, but should there be, the joker being "wild" may be played for this letter. Where the joker is used in the game the player holding the same may play it at any time he desires to 95 complete a word, the letter for which he does not hold in his hand.

From the above it will be seen that the games which may be played with these cards are not only interesting and amusing to the 10 players but are highly instructive as those playing the game will readily learn to spell and the game should also increase the vocabulary, playing the game to any extent, as it will be seen that the greater number of 10 words a person has at their command, the more chance they have of scoring points in the game.

Although the drawings and above specification disclose the best mode in which I 11 have contemplated embodying my invention I desire to be not limited to the details of such disclosure, for, in the further practical application of my invention, many changes in form and construction may be made, as 11 circumstances require or experience suggests, without departing from the spirit of the invention, within the scope of the appended claim.

I claim:—

A set of cards containing four complete alphabets, each card containing two different letters of the alphabet to be played selectively, the combination of letters upon each card differing from each other card in the 1 deck.

In testimony that I claim the above, I have hereunto subscribed my name.

SCOTT HORACE FEERO.
